Fig. 3

UNITED STATES PATENT OFFICE.

LESLIE W. CLAYBOURN, OF MILWAUKEE, WISCONSIN.

MIXING MACHINE.

Application filed December 11, 1925. Serial No. 74,773.

My invention relates to mixing machines employable for various purposes and in various relations. It is employable for instance in a step of the method set forth, described and claimed in my application for improvements in method of conditioning printing ink, Serial No. 74,774, filed December 11, 1925, copending herewith. My improved machine is also applicable in other relations, for instance, in grinding or mixing ingredients for the preparation of prescriptions for medicinal use, and for other purposes.

It is the object of my invention to provide a mixing machine comprising a rotary stirrer or reducing tool having an axis of rotation at an angle between the vertical and horizontal and coacting with a bowl having an inclined wall for retaining the material being treated; further, to cause relative rotation between said rotary reducing tool and said bowl on an axis substantially coincident with the axis of the bowl; further, to provide novel means whereby to cause coaction between said rotary reducing tool and the bowl; further, to provide novel means whereby to cause separation between the rotary reducing tool and driving means for the same; further, to provide novel means whereby to provide various coacting relations between the rotary reducing tool and nested bowls; and, further, to provide novel means for mounting the driving means.

The invention will be further readily understood from the following description and claims, and from the drawings, in which latter:

Fig. 1 is a front elevation of my improved device showing the same provided with a cabinet for supporting the mixing device.

Fig. 2 is a side elevation of the same showing the bowl and the driving means tilted, and the cabinet partly broken away.

Fig. 3 is a central vertical axial section of my improved device, taken in the plane of the line 3—3 of Fig. 2, showing the parts in connected relation for mixing in full lines, with the main bowl in up-position, and the reducing tool as a roller, and showing the tilting frame in tilted position in dotted lines, partly broken away, the cabinet being partly broken away.

Fig. 4 is a similar section, showing the main bowl in down position, and provided

with an inner bowl nested therein, and showing the reducing tool as a stirrer in coactive relation with the inner bowl.

Fig. 5 is a detail in end elevation taken in the direction of the line 5—5 of Fig. 4, showing the bowl positioning means.

Fig. 6 is a horizontal section of the same, taken on the irregular line 6—6 of Fig. 5.

Fig. 7 is a detail in front elevation showing the latching means for the pivoted frame.

Fig. 8 is a cross-section of the same, taken on the line 8—8 of Fig. 7; and,

Fig. 9 is a cross-sectional detail taken in the plane of the line 9—9 of Fig. 4.

The frame of the machine as exemplified comprises a base 11, from which pedestals 12, 13, extend upwardly. These pedestals are provided with bearings 14, in which eccentric bearings 15 are journaled. A mixing bowl 17 is provided with trunnions 18, which are journaled in the eccentric bearings. These trunnions are shown in the form of shoulder bolts, threaded into threaded holes in bosses 19 on the wall of the mixing bowl, arranged for readily disengaging and removing the mixing bowl and reassembling the same on the frame.

Each of the eccentric bearings is provided with an arm 21, having a handle 22 extending therefrom, for shifting the eccentric bearings in order to raise or lower the bowl. When the bowl 17, which may be referred to as the main bowl, is in raised position, the coaction of the tool therein takes place directly with the inner face of the wall of the bowl, which relation is illustrated in Fig. 3. The mixing bowl is arranged to be lowered in order to receive a bowl 23, which may be nested therein, as illustrated for instance, in Fig. 4, in which relation the tool, while retaining its path of rotation, coacts with the inner face of the inner bowl.

The bowl is fixed in adjusted positions, as by providing each of the handles 22 with a pull-pin 24, which is arranged to be selectively received in holes 25, 26, for positioning the eccentric bearings. Each of the pull-pins is normally urged into coaction with its hole by a spring 27, between a shoulder 28 on the pull-pin and a plug 29 at the outer end of a socket 30, in which the spring is located.

The bowl is arranged to be tilted when de-

sired for emptying its contents. The position of the bowl may be fixed by a pull-pin 31, which is located on the pedestal 12, and is arranged to be selectively received in holes 32, 33, in one of the bosses 19 of the bowl. This pull-pin is urged into the hole registering therewith, as by a spring 34 between a shoulder 35 on the pull-pin and a plug 36 threaded into the outer end of the bore 37 in which said pull-pin is located. The pull-pin is provided with a handle 38.

A lug 41 on the bowl coacts with one of the pedestals 12 for limiting the swinging movements of the bowl. This lug is arranged to impinge against the front face 42 on the pedestal, when the bowl is in down position, and against the face 43 at the upper end of said pedestal, when the bowl is in up position, the lug moving along an arcuate face 44 at the upper corner of said pedestal.

The reducing tool is arranged to be driven by a pinion 51, the hub 52 of which rotates in a bearing 53, the pinion being held endwise in said bearing by a nut 54 threaded to said hub, with the bearing shouldered between said pinion and said nut. An internal gear 55 coacts with the pinion, and is exemplified as an annular beveled rack having inclined teeth, with the pinion having a planetary movement about the annular rack.

There is releasable driving connection between the pinion and the rotating reducing tool, exemplified by providing the reducing tool with a socket 56 and the pinion and its hub with a socket 57, a shank 58 being received in said sockets and having driving connections with both the pinion and the tool, as by forming said shank and the walls of said sockets polygonal in cross-section, the same being shown square. The shank is provided with a handle 59. Axial movement of the shank outwardly releases driving connection between the pinion and the tool, and permits the movement of the pinion for release and removal of the tool.

A pivoted frame 61 is pivoted to the main frame, and is exemplified as having a depending bearing 62, received between bearings 63, on arms 64, extending from the pedestal 13. A pivot pin 65 is received through said bearings and held endwise therin, as by bolts 66 threaded into axially threaded holes at the respective ends of said pin, washers 67 being received between the heads of said bolts and the outer bearings 63 respectively.

The pivoted frame comprises a ring structure 71 having an annular rabbet 72 at its inner face in which the annular rack 55 is secured, as by means of screws 73.

A rotatable ring 75 is arranged to rotate on said pivoted frame, and is held thereto by a positioning ring 76 provided with an annular rabbet 77 in which an annular lug

78 of the rotatable ring is journaled. The positioning ring is secured to the ring structure, as by screws 79.

The bearing 53 is located on a bracket 81 of the rotatable ring, and moves planetwise with the rotatable ring.

The axis of rotation of the pinion 51 and of the rotatable tool rotating therewith is preferably at an angle between the vertical and horizontal. The bowl preferably has a sloping inner wall, this inner wall being substantially conical in shape and provided with a seat 82 for the inner end 83 of the rotatable tool. The slope of the inner face of the wall of the bowl is represented at an angle differing from the angle of the axis of rotation of the rotatable tool. The construction shown is such as to provide a path of rotation for the outer face of the tool which is also substantially conical for coacting throughout its length with the inner periphery of the bowl.

The rotatable tool is in Fig. 3 exemplified as having an outer periphery in the form of a roller 84, and in Fig. 4 is represented of skeleton form, shown at 85, and as having a shank 86 of small cross-section, provided with the reversely bent portion 87. Other forms of rotatable tools may also be provided, depending on the manner of agitation, grinding action or mixing qualities desired. The inner end of each of the tools preferably is rounded like the sector of a ball, as shown at 83, and bears in the lower end 82 of the bowl, forming substantially a step bearing for the rotary tool. Upward movement of the tool is limited by the pinion 51.

The tool is thereby positioned endwise and by its connection with the pinion and its step bearing is held toward the wall of the bowl in manner preferably to create a grinding effect and scraping action between the outer periphery of the tool and the inner wall of the bowl. This grinding effect, when the tool takes the form of a roller, as in Fig. 3, is substantially throughout the outer periphery of the tool, and in a skeleton tool, such as shown in Fig. 4, is throughout the outermost portion of the outer periphery of the tool, for creating intermittent grinding, rubbing or scraping effects upon said inner wall, and thereby pinching and disintegrating the material being ground or mixed between the tool and the wall of the bowl, and scraping the material from said wall to mix the material. The coaction between the lower ends of the tool and bowl is similar to the coaction between a pestle and mortar for causing additional disintegration and mixing of the materials.

The skeleton tool, as shown in Fig. 9, may be provided with a scraping edge 88 and a roller section 89, which coact with the inner face of the bowl to scrape the same and reduce the material.

The angular direction of the axis of the

rotatable tool to the inclination of the portion of the wall of the bowl with which it momentarily coacts, and the conelike form of the outer periphery, or path of rotation 5 of the outer periphery, of the tool, and the diameter of the pinion with relation to said path, is to cause variations in speeds between 10 said rotary path and the inner wall of the bowl at different points lengthwise of the rotary tool. Thus the rubbing speed between the part of the tool of greater diameter and the wall of the bowl is greater than the speed of attrition movement between the smaller part of the tool or its path and the 15 inner wall of the bowl, thus creating a variation in action throughout various heights of the material for further aiding in thorough mixing of the material. The skeleton form of tool also produces a whipping effect 20 upon the material for further aiding in mixing, disintegrating and aerating the same and conditioning the material.

The rotatable ring 75 is shown provided with a crown gear 91 extending downwardly, 25 constituting the same a ring-gear, the teeth of which move in an annular recess 92 in the ring structure 71. A pinion 93 meshes with the ring-gear and is shown fixed to a shaft 94 journaled in a bearing 95 of the pivoted frame, the shaft being rotated by the 30 rotor of an electric motor 96 shown fixed in inverted position to the lower face of a bracket 97, shown as part of the pivoted frame. The motor may be a variable speed 35 motor for imparting various speeds to the mixing devices.

The upper end of the bowl is received in an annular recess 101 in the lower face of 40 the pivoted frame. The bowl is preferably provided with an annular guiding face 102 coacting with the annular wall of said recess.

The swinging frame is arranged to be held in down position by a latch, which is shown comprising a lever 105, pivoted on a lug 106 on the positioning ring 76, and provided with a handle 107 for manipulating the latch and for raising and lowering the swinging frame. The lever is provided with a cross lug 108, which is arranged to be received under a lug 109, on an arm 110, extending from the pedestal 12. A spring 111 is fixed, as by a screw 112, in a recess 113 in the lug 109, and is provided with a yielding retaining part behind which the cross-lug 108 is received when the pivoted frame is held for coactive relation between the operating parts and the rotatable tool. The arm 110 is provided with a seat 114, on which the swinging end of the pivoted frame 60 is arranged to rest when the parts are in coactive relation.

The ring-gear is preferably provided with an annular shield 115, having a downwardly sloping flange 116, received over the internal gear. This shield is fixed as by screws

117 to the inner face of the ring-gear. This shield preferably extends throughout the inner face of the ring-gear, the respective ends thereof connecting with the bracket 81. The bracket is provided with a downwardly extending shield 118 received about the pinion 51.

When it is desired to tilt the pivoted frame, the pinion 51 is brought to a position of rest substantially in line with the axis of the 75 pinion 93, and the shank 58 is moved outwardly axially so as to disconnect said shank from the tool. The swinging of the handle 107 upon its pivot and the movement of the handle upwardly so as to swing the pivoted 80 frame on its pivot, moves the pivoted frame upwardly away from the bowl, leaving the tool in the bowl, which may thereupon be also removed preferably after scraping the ink or other material adhering thereto into 85 the bowl.

This construction prevents the dragging of material with the pivoted frame in the swinging movement of the latter and maintains the material in the bowl.

The level of the material in the bowl is preferably restricted to a level below the upper shoulder 119 of the tool, so as to avoid the movement of the material upwardly beyond the upper edge of the bowl or into 95 the gearing. Observation of the material and the progress of the crushing, mixing, aerating and conditioning of the material may be had through the space within the ring members. Pallette knives or other tools, which it may be desired to employ in the bowl, may be inserted through said space while the conditioning of the material is taking place.

When the pivoted frame is tilted, the motor frame is arranged to be received in an opening 120 between the arms 64, the motor frame being cushioned against an elastic bumper 121 on the pedestal 13.

The location of the pivot 65 of the pivoted frame with relation to the gearing, the connection between the gearing and the rotary tool, the joint between the bowl and the pivoted frame, and the connection between the pivoted frame and its seat on the pedestal 12, are such as to provide for ready clearance between all said parts upon pivotal movement of said pivoted frame. The position of said pivot is also such that when the pivoted frame is tilted for exposing the bowl, it will remain in tilted position by gravity. The gear frame and the motor are at opposite sides of the pivot for aiding in balancing the pivoted frame and rendering its manipulation easy.

When emptying the bowl, the bowl may be tilted, the pull-pin 31 having been released from its hole, for draining the bowl into a pan 125 on a table 126, which may be the top of a cabinet, exemplified at 127, to which 130

the base of the machine is secured in suitable manner. The bowl may be maintained in decanting position by reception of the pull pin 31 in the hole 32.

5 Provision is made for supplemental bowls, of which a suitable number may be provided. Such supplemental bowls are exemplified as bowls 131, which may be formed up out of sheet metal, and be an inner or 10 auxiliary bowl received within the main bowl 17. It may be provided with handles 132, of which there may be a pair at opposite sides of the bowl. These handles are shown as extending inwardly and will be received in the space 133 between the upper end of the tool and the overhanging ledge formed by the ring structure above the bowl, so that the tools may readily pass the handles.

20 When the material has been thoroughly conditioned in said supplemental bowl, the supplemental bowl may be raised out of the main bowl when the pivoted frame has been tilted. The supplemental bowl is preferably received in a bowl-stand for holding the same in upright position, such a bowl-stand being shown at 135, provided with an inner frusto conical seat 136 in which the supplemental bowl is supported. This stand 25 may also be provided with handles 137.

30 A suitable number of such bowl stands is provided. They are especially useful when it is desired to condition different materials, as when conditioning printing inks of different colors, which are intended for substantially simultaneous use. The cabinet may be provided with shelves 138 for supporting the bowl-stands, tools and other parts, and packages of materials, and be provided with 35 hinged doors 139 for closing the same.

Having thus fully described my invention what I claim as new, and desire to secure by Letters Patent, is:

1. In a mixing machine, the combination 45 of a main frame, a gear-frame pivoted thereto, a ring-gear rotatable therein, a mixing bowl pivoted to said main frame, and a rotatable tool in said mixing bowl, said ring-gear coacting with said rotatable tool in said mixing bowl, and the pivotal axes of said gear-frame and of said mixing bowl being in separated relations to each other for non-interferingly tilting said gear-frame and said mixing bowl respectively.

50 2. In a mixing machine, the combination of a main frame, and a mixing bowl and pivoted frame coacting with each other and pivoted to said main frame, said mixing bowl and said pivoted frame comprising parts which are normally located in separated horizontal planes and which move into a common horizontal plane when said mixing bowl and said pivoted frame are pivotally moved into discharge positions, the pivotal axes of said mixing bowl and said piv-

oted frame being at angles with relation to each other for moving said mixing bowl out of the path of pivotal movement of said pivoted frame.

3. In a mixing machine, the combination 76 of a main frame, a mixing bowl therein, and a pivotal gear-frame having a substantially horizontal pivotal axis comprising gearing including a ring-gear about the upper end of said mixing bowl at one side of said pivot 78 and a motor at the other side of said pivot for driving said gearing and arranged for counter-balancing said pivotal gear-frame.

4. In a mixing machine, the combination 80 of a main frame, a bowl therein, a gear-frame pivoted to said main frame on a substantially horizontal axis in a plane below the top of said mixing bowl and arranged to swing upwardly and away from said bowl, gearing on said gear-frame at one side of the 85 pivot of said gear-frame arranged for operating a reducing tool in said mixing bowl, and an electric motor on said gear-frame arranged to swing downwardly at the other side of said pivot whereby to counter-balance 90 said gear-frame.

5. In a mixing machine, the combination 95 of a main frame, a mixing bowl therein, and a gear-frame coacting with said mixing bowl and provided with a pivot for swinging said gear-frame away from said mixing bowl, said gear-frame normally in substantially horizontal position, and said pivot located below the major portion of the weight of said gear-frame when said gear-frame is in 100 said last-named position, and arranged whereby to swing said gear-frame away from said mixing bowl for placing said major portion of said weight of said gear-frame at that side of said pivot removed from said 105 mixing bowl.

6. In a mixing machine, the combination 110 of a main frame, a mixing bowl therein, a gear-frame having a substantially horizontal pivot on said main frame, gearing on said 115 gear-frame arranged for operating a reducing tool in said mixing bowl and arranged to swing upwardly and away from said bowl, said gearing located at one side of said pivot, said gear-frame comprising a bracket at the other side of said pivot, and an electric motor under said bracket for operating said gearing and arranged to swing downwardly at the other side of said pivot whereby to counter-balance said gear-frame. 120

7. In a mixing machine, the combination 125 of a main frame, a mixing bowl therein, a normally substantially horizontal gear-frame comprising gearing above said mixing bowl, said gear-frame comprising a laterally extending bracket, an electric motor secured to said bracket substantially in the plane of said gearing, and a substantially horizontal pivot on said main frame for said gear-frame between said motor and 130

said gearing, said main frame provided with a recess in which said motor is received when said gear-frame is moved on said pivot to raise said gearing with relation to said mixing bowl.

8. In a mixing machine, the combination of a mixing bowl, a reducing tool therein, a gear-frame having a pivot at the side of said mixing bowl, gearing on said gear-frame comprising a gear for rotating said reducing tool, said reducing tool and said gearing provided with axially aligned walls, and a rigid connection coacting with said walls of both said reducing tool and said gearing for rotatively attaching said reducing tool to said gearing, said connection axially movable for release relation between said gear and said reducing tool whereby to release said reducing tool from said gear-frame and permit said gear-frame to swing on said pivot and leave said reducing tool in said mixing bowl.

9. In a mixing machine, the combination of a mixing bowl having a wall whose inner face is substantially conical in shape, a reducing tool whose outer periphery has a path of rotation which is substantially conical in shape and coacts with said inner face, and means for rotating said reducing tool comprising a pinion about the axis of rotation of said reducing tool and an internal gear meshing with said pinion substantially concentric with the end of greater diameter of said bowl, and constructed and arranged whereby to rotate said reducing tool on an axis which is at an angle to the axis of said mixing bowl and to the sector of said inner face nearest said reducing tool.

10. In a mixing machine, the combination of a mixing bowl having a wall whose inner face is substantially conical in shape, a reducing tool whose outer periphery has a path of rotation which is substantially conical in shape and coacts with said inner face, and means for rotating said reducing tool comprising a pinion about the axis of rotation of said reducing tool and an internal gear meshing with said pinion substantially concentric with the end of greater diameter of said bowl, and constructed and arranged whereby to rotate said reducing tool on an axis which is at an angle to the axis of said mixing bowl and to the sector of said inner face nearest said reducing tool, and said axes intersecting at substantially the bottom of said mixing bowl.

11. In a mixing machine, the combination of a mixing bowl having a wall whose inner face is substantially conical in shape, a reducing tool whose outer periphery has an attrition face which has a path of rotation which is substantially conical in shape and which throughout said attrition face contacts with said inner face, and means whereby the axis of rotation of said reducing tool

and said mixing bowl have a relative planetary movement between them, the axes of rotation for said planetary movement and of said reducing tool and the apex of said inner face having closest approach at substantially coincident points.

12. In a mixing machine, the combination of a mixing bowl having an inner face which tapers toward its bottom and is provided with a seat at its bottom, a rotatable reducing tool having an axis of rotation at an angle to the axis of said mixing bowl, and whose outer periphery coacts with said inner face and whose lower end is stepped in said seat, gearing for rotating said reducing tool, means whereby said reducing tool is confined for limiting axial movement thereof with relation to said seat, means for moving said gearing in axial direction away from said reducing tool, and a releasable connection between said gearing and said reducing tool.

13. In a mixing machine, the combination of a mixing bowl having an inner seat in its bottom, a reducing tool in said mixing bowl having a lower end stepped in said seat, gearing, releasable driving connection between said gearing and said reducing tool, means for releasing said driving connection by movement away from said mixing bowl, and means whereby to tip said mixing bowl.

14. In a mixing machine, the combination of a mixing bowl having an inner seat in its bottom, a reducing tool in said mixing bowl having a lower end stepped in said seat, gearing, releasable driving connection between said gearing and said reducing tool, means for releasing said driving connection by movement away from said mixing bowl, means whereby to tip said mixing bowl, and means for positioning said mixing bowl for coactive relation between said reducing tool and said gearing.

15. In a mixing machine, the combination of a mixing bowl, a gear-frame above said mixing bowl comprising a ring structure, an internal gear-rack on said ring structure, a ring-gear coacting with said ring structure, a pinion meshing with said internal gear-rack and journaled with an inclined axis on said ring-gear, a reducing tool in said mixing bowl, and a releasable connection between said reducing tool and said ring-gear.

16. In a mixing machine, the combination of bowl supporting means, an annular rack and planetary gear structure above said bowl supporting means arranged for imparting rotary and planetary movements to a reducing tool, nested bowls supported by said bowl supporting means, and means for adjusting said bowl supporting means for coaction of the inner walls of said respective bowls with said reducing tool.

17. In a mixing machine, the combination of bowl supporting means, an annular rack

- and planetary gear structure above said bowl supporting means arranged for imparting rotary and planetary movements to a reducing tool, nested bowls supported by said bowl 5 supporting means, said annular rack and planetary gear structure comprising an annular recess having a wall for guiding axial bowl movement, and means for adjusting said bowl supporting means for axial movement of the bowl supported thereby along said annular wall.
18. In a mixing machine, the combination of a mixing bowl, a gear-frame above said mixing bowl comprising a ring structure, an 15 internal gear-rack on said ring structure, a ring-gear coacting with said ring structure, a pinion meshing with said internal gear-rack and journaled on said ring-gear, a reducing tool in said mixing bowl, a releasable 20 connection between said reducing tool and said ring-gear, and an annular shield on said
- ring-gear extending over said internal gear-rack.
19. In a mixing machine, the combination of a mixing bowl having a substantially conical inner face and a seat in its bottom, a driving gear, and interchangeable reducing tools respectively having lower ends stepped in said seat, upper ends stepped by said driving gear and outer peripheries provided with attrition faces having paths of rotation of different diameters lengthwise of the axes of rotation of said tools and which throughout their extents coact with said inner face, and the axis of said bowl, the axis of rotation of 30 said reducing tool and the apex of said conical inner face having closest approach at substantially coincident points for coaction between said tools and said inner face.
- In testimony whereof, I have hereunto 40 signed my name.

LESLIE W. CLAYBOURN.
